STRAP AND BUCKLE ASSEMBLING
APPARATUS

Harry Alfandre, Brooklyn, N. Y.

Application June 10, 1935, Serial No. 25,957

11 Claims. (Cl. 223—49)

This invention relates to a device for facilitating the insertion of straps or tapes through the openings in buckles or similar members. Although the device is adapted for other purposes, it is intended primarily for use in the manufacture of adjustable shoulder straps of the type extensively utilized in ladies' undergarments.

In one well known construction of adjustable shoulder or similar straps, two strips of tape are looped through openings in a pair of buckles, one buckle having a single eyelet and the other buckle having a double eyelet defined by the sides of the buckles and an intermediate bar. In the case of shoulder straps, the buckle eyelets are relatively small and it is difficult and time consuming to pass the ends of the tape through the eyelets, especially in the case of the double eyelet buckle because the strip of tape directly associated therewith for forming the adjustable loop is twice passed through the eyelets. Owing to these difficulties, the cost of the labor necessary to assemble the tapes with the buckles in forming the adjustable loop has been disproportionately large, and owing to the length of time necessary to assemble the buckles with the tapes, production of the garments in which the adjustable straps are used is frequently delayed. It is therefore the object of the present invention to eliminate these difficulties and delays, and to substantially reduce the cost of manufacture of adjustable shoulder straps or similar articles.

With this object in view, I have constructed a device which greatly facilitates the insertion of the tapes through the buckles, thereby considerably reducing the cost of producing adjustable shoulder straps and accelerating the production of the straps and the garments provided therewith. For a complete understanding of the invention, reference is to be had to the following description and to the accompanying drawings.

In the drawings:

Fig. 1 is a side view of a device constituting one embodiment of the invention;

Fig. 2 is a sectional view on the line 2—2 of Fig. 1, on an enlarged scale, with parts broken away for the sake of clearness in illustration;

Fig. 3 is a front view of the device, on an enlarged scale;

Fig. 4 is a sectional view on the line 4—4 of Fig. 1, on an enlarged scale;

Fig. 5 is a sectional view on the line 5—5 of Fig. 2, on an enlarged scale;

Fig. 6 is a sectional view on the line 6—6 of Fig. 3;

Figs. 7 and 8 are perspective views of buckles

which may be assembled with straps or tapes according to the present invention on an enlarged scale in the ratio 2:1:

Figs. 9 and 10 are end and plan views, respectively, of an adjustable shoulder strap of a well known form in which the buckles shown in Figs. 7 and 8 are utilized.

Referring to the drawings in detail, the apparatus here shown comprises a frame which may include the top 10 of a bench or table, a bar 12 fixed thereto, and a post 14 also fixed to said bench top in upstanding vertical relation thereto. Two pairs of jaws 16 and 18, respectively, are carried by the bar 12 and are arranged in vertically spaced relation below a blade 20 carried by a rod 22. Said rod is movable in bearing openings 24 in the ends 25 of a U-shaped guide 26 which is carried by a bracket 28 having its ends fixed to the bar 12 and to the guide 26 by screws 30.

A lever 32 for actuating the rod 22 is pivotally connected at the upper end of the post 14 by a pivot screw 34. The forward end of the lever 32 has a pivotal connection 36 with the upper end of the rod 22 to permit arcuate movement of said end of the lever, while the movement of the rod is confined to a rectilinear path. As the lever 32 is disposed laterally of the rod 22, a bracket 38 of inverted-L shape, which as here shown is secured to the lever by rivets 40, is utilized for transmitting movement of the lever to the pivotal connection 36. As best shown in Fig. 3, said pivotal connection comprises a fixed coupling member 42 secured to the horizontal bracket arm 39 and an H-shaped coupling member 44 pivotally secured to the fixed coupling member 42 and to the upper end of the rod 22 by pivot pins 46 and 48, respectively.

For the purpose of preventing the rod 22 from turning in the bearing openings 24, guide members 50 are adjustably secured to said rod in spaced relation by screws 52. Each guide member 50 has a flat end surface 54 in slidable engagement with a corresponding flat surface 56 on the guide member 26. In addition to their function as guides for the rod 22, the members 50 also constitute stop means to limit the movement of the rod 22 in both directions, the upper member 50 constituting a stop member to limit the movement of the rod upwardly or to retracted position and the lower member 50 constituting a stop member to limit the movement of the rod downwardly or to projected position.

A tension spring 58 is secured by eyelet screws 60 to the rear end of the lever 32 and to the bench 55

10 for resiliently opposing the movement of said lever and the rod 22 to work engaging position and for returning said rod to retracted position. A pull member 62, which may consist of a cord, 5 chain, or rod, is secured at one end to the lever 32 and at its lower end may be connected to a foot treadle (not shown) for operating the lever 32 to move the rod 22 and the blade 20 carried thereby to projected position against the force 10 of the spring 58.

Each pair of jaws 16 and 18 comprises fixed and movable opposed jaw members 64 and 66, respectively, consisting of relatively thin strips of metal having their rear portions positioned within 15 slots 68 in the sides of the bar 12. The jaw members 64 are secured in fixed relation in said slotted portion of the bar 12 by pins 70, while each movable jaw member 66 is mounted for movement within its companion slot 68 on a pivot 20 pin 72 and is urged toward its companion fixed jaw member 64 by a compression spring 74 which is positioned within a hole 76 in the bar 12 and engages the rear edge of said movable jaw member. A combined stop and guide member 78 is 25 fixed to each of the stationary jaw members 64 in spaced relation to the free ends of the latter and is provided with a guide opening 80 in which the free end portion of the movable jaw member 66 is movably received, as best shown in Fig. 4. 30 The vertical wall 82 of the opening 80 constitutes a stop for the movable jaw 66. Thus, the companion jaws 64 and 66 of each pair of jaws 16 and 18 extend forwardly in spaced relation providing at the free ends of each pair of jaws a 35 front opening for the insertion and the removal of the buckles with which the tapes are to be assembled. The forward inner edges of the jaws 64 and 66 have grooves 61 to receive the sides of the buckles. As the pairs of jaws 16 and 18 are 40 intended to receive buckles of different widths, the upper pair of jaws 16 are normally more widely spaced than the lower pair of jaws 18, and for this purpose, the intermediate portions 84 of the members 78 are of different widths, as illustrated 45 in Fig. 3. Thus, referring to Fig. 5, a double eyelet buckle 85 is received between the jaws 64 and 66 of the upper pair 16, while a single eyelet buckle 88 is received between the jaws 64 and 66 of the lower pair 18. It will be observed that 50 although the companion jaws of the upper and lower pairs are differently spaced, the arrangement is such that the openings 87 in the double eyelet buckle 85 is in vertical alignment with the opening 89 in the single eyelet buckle 88. When 55 the buckles are inserted in the jaws through the open ends of the latter, they are moved into engagement with the intermediate portions 84 of the members 78 which thus constitute means to position the buckles within the jaws. 60 As the ends of the buckles are rounded, the buckles are readily inserted between the jaws by engaging their rounded ends with the free ends of the jaws in the grooves 61 and by pressing on the opposite ends of the buckles, the movable jaw members yielding to the pressure thus exerted and moving away from the fixed jaw members to 65 permit the buckles to enter between the jaws without necessitating a separate movement of the movable jaws and making it unnecessary to 70 perform a separate operation in holding the jaws apart while the buckles are inserted. Similarly, after the tapes are inserted through the openings, the buckles can be readily removed through the front open ends of the jaws by merely pulling the 75 buckles through said openings.

In accordance with the present invention, a holder 90 for the buckle-equipped straps is mounted on the frame of the apparatus. The holder 90 comprises a round rod 92 having a reflexed end portion 94 pivotally mounted within an opening 96 in the bar 12 and adjustably secured in said opening by a wing-screw 98, the other end 99 of the rod 92 extending vertically and being provided with a socket 100 within which there is secured a slender rod 102 which may be in the form of a needle or pointed pin, on which the ends of one of the straps looped through the opening 89 of the buckle 88 may be held as illustrated in Fig. 5.

In using the present device for the purpose of assembling the buckles with the straps and in forming the adjustable loop in one of the straps, a single eyelet buckle 88 is inserted between the lower pair of jaws 18. One of the strap sections is then placed on the jaws 64 and 66 over the opening in the buckle held thereby, and the lever 32 is then actuated to depress the rod 22 to project the blade 20 in engagement with the strap and through the opening in the buckle, thereby forcing the strap through the buckle opening. The ends of the strap which have, in this manner, been looped through the buckle are then impaled on the pin 102 as illustrated in Fig. 5 so that the intermediate folded portion 104 of the strap is held at one side of the buckle opening. Next the double eyelet buckle 85 is inserted between the upper pair of jaws 16. The other strap section is then threaded through the opening 86 by passing one end of the strap upwardly through said opening, and a suitable length of the strap thus passed through the opening 86 is positioned over the buckle opening 87, after which the blade 20 is projected into engagement with said overlying portion of the strap, forcing the latter through the buckle opening 87 of the buckle 85 and also through the buckle opening 89 of the buckle 88. Then the portion of the strap thus passed through the buckle openings 87 and 89 in the two buckles is again threaded through the buckle opening 86 and is again disposed in overlying relation with respect to the buckle opening 89, after which the blade 20 is again projected to engage the last mentioned overlying portion of the strap to force the latter through the buckle opening 87, but not through the opening 89 in the buckle 88. In this manner, the two buckles are assembled with the strap and an adjustable loop is formed in the strap section which is looped through both of the buckles. The buckles thus assembled with the straps are then removed from the jaws, and may be left suspended on the pin 102 of the holder 90.

A well known form of adjustable strap which is produced according to the present invention is illustrated in Figs. 9 and 10. This adjustable strap comprises a strap section 103 which is threaded through the opening 89 of the single eyelet buckle 88 in the manner described above and a strap section 106 threaded through the openings in both buckles to provide the adjustable loop 108. It will be understood, however, that the present apparatus may be utilized with other types of buckles and other types of straps or tapes.

It is thus seen that the embodiment of the invention disclosed herein is well adapted to accomplish the objects of the invention. It will be understood, however, that the invention is capable of other embodiments and that in the present embodiment certain changes in the construc- 70

tion and arrangement of parts may be made and that certain parts may be used without others. Therefore, I do not wish to be limited to the precise construction herein shown and described, except as may be required by the appended claims and the prior art.

Having thus described my invention, what I claim and desire to secure by Letters Patent of the United States is:

- 10 1. A device of the class described comprising a frame, a plurality of pairs of jaws positioned on said frame, the jaws of each pair being constructed and arranged to hold a buckle having an opening therethrough with an opening of the buckle held by one pair of jaws in alignment with the opening in a buckle held by another pair of jaws, the jaws of each pair having confronting edges between which the buckle is held, and a number movable between and transversely of said confronting edges for threading a strap through the openings in the buckles held by said pairs of jaws, said member being normally free from engagement with said strap and movable in one direction to engage the strap and force the same through the buckle openings and movable in the opposite direction away from said strap without retracting the latter through said openings.
- 15 2. A device of the class described comprising a frame, a plurality of pairs of jaws positioned on said frame, the jaws of each pair being relatively movable and constructed and arranged to hold a buckle having an opening therethrough with an opening of the buckle held by one pair of jaws in alignment with the opening in a buckle held by another pair of jaws, the jaws of each pair having confronting edges between which the buckle is held, and a member movable between and transversely of said confronting edges for threading a strap through the openings in the buckles held by said pairs of jaws, said member being normally free from engagement with said strap and movable in one direction to engage the strap and force the same through the buckle openings and movable in the opposite direction away from said strap without retracting the latter through said openings.
- 20 3. A device of the class described comprising a frame, a plurality of pairs of jaws positioned on said frame, the jaws of each pair being constructed and arranged to hold a buckle having an opening therethrough with an opening of the buckle held by one pair of jaws in alignment with the opening in a buckle held by another pair of jaws, the jaws of each pair having confronting edges between which the buckle is held, and a blade movable transversely of said jaws and having a dull free edge engageable with a strap for inserting the latter through the eyelet of said buckle, a reciprocating rod carrying said blade, a guide for said rod, a pivoted lever for actuating said rod, and means for connecting said rod in movable relation to said lever.
- 25 4. A device of the class described comprising a frame, a holder positioned on said frame and constructed and arranged to receive a member having an opening therethrough, said holder comprising parts relatively movable in a single plane and having confronting edges adapted to

grip said member therebetween and resilient means for yieldingly urging one of said parts toward the other to yieldingly engage said member, and a reciprocating member movable between and transversely of said confronting edges for threading a strap through said opening, said reciprocating member being normally free from engagement with said strap and movable in one direction to engage the strap and force the same through said opening and movable in the opposite direction away from said strap without retracting the latter through said opening.

5 5. A device of the class described comprising a frame, a holder having spaced jaws positioned on said frame and constructed and arranged to receive an eyelet buckle therebetween, a blade movable transversely of said jaws and having a dull free edge engageable with a strap for inserting the latter through the eyelet of said buckle, a reciprocating rod carrying said blade, a guide for said rod, a pivoted lever for actuating said rod, and means for connecting said rod in movable relation to said lever.

10 6. A device of the class described comprising a frame, a holder having spaced jaws positioned on said frame and constructed and arranged to receive an eyelet buckle, a blade movable transversely of said jaws and having a dull free edge engageable with a strap for inserting the latter through the eyelet of said buckle, a reciprocating rod carrying said blade, a guide for said rod, a pivoted lever for actuating said rod, and a connection between said lever and rod comprising a link pivoted to said rod.

15 7. A device of the class described comprising a frame, a plurality of pairs of jaws positioned on said frame, the jaws of each pair being constructed and arranged to hold a buckle having an opening therethrough with an opening of the buckle held by one pair of jaws in alignment with the opening in a buckle held by another pair of jaws, the jaws of each pair having confronting edges between which the buckle is held, a blade movable transversely of said jaws and having a dull free edge engageable with a strap for inserting the latter through the openings in the buckles, a reciprocating rod carrying said blade, a guide for said rod, a pivoted lever for actuating said rod to reciprocate in said guide, and means for connecting said rod in movable relation to said lever.

20 8. Apparatus for facilitating the assembly of a plurality of apertured members with strips of tape to form an adjustable strap, said apparatus comprising means for releasably holding two apertured members in fixed spaced relation with apertures in the two members in alignment, in combination with means adapted to engage a strip of tape and force the same through the aligned apertures of the two members comprising a member normally free from engagement with said strip and movable in one direction to engage the latter and movable in the opposite direction away from said strip without retracting the same through said apertures.

25 9. Apparatus for facilitating the assembly of a plurality of apertured members with strips of tape to form an adjustable strap, said apparatus comprising a frame, means on the frame for releasably holding two apertured members in fixed spaced relation with apertures in the two members in alignment, in combination with means mounted on said frame and movable therein adapted to engage a strip of tape and force the same through the aligned apertures of the two

members comprising a member normally free from engagement with said strip and movable in one direction to engage the latter and movable in the opposite direction away from said strip 5 without retracting the same through said apertures.

10. A device of the class described comprising a frame, a plurality of spaced pairs of jaws positioned on said frame, the jaws of each pair being adapted to hold a buckle having an opening therethrough with an opening of the buckle held by one pair of jaws in alignment with the opening in a buckle held by another pair of jaws to permit the substantially simultaneous insertion of a 15 strap through the aligned openings in the buckles held by said pair of jaws, the jaws of each pair having spaced confronting edges provided with grooves to receive the opposite edge portions of the buckles and means for inserting a strap 20 through said aligned buckle openings comprising a member normally free from engagement with said strap and having a free dull end, said member being movable in one direction for engagement of said dull end with the strap for forcing the latter through said openings and movable in the opposite direction away from said strap and without retracting the latter through 25 said openings.

11. A device of the class described comprising a frame, a plurality of spaced pairs of jaws positioned on said frame, the jaws of each pair being adapted to hold a buckle having an opening therethrough with an opening of the buckle held by one pair of jaws in alignment with the opening in a buckle held by another pair of jaws to permit the substantially simultaneous insertion of a strap through the aligned openings in the buckles held by said pair of jaws, the jaws of 10 each pair having spaced confronting edges provided with grooves to receive the opposite edge portions of the buckles, said grooves having open forward ends to permit the removal of the buckles from said jaws by moving said buckles 15 longitudinally of the grooves toward their open ends while said buckles are engaged by said jaws, and means for inserting a strap through said aligned buckle openings comprising a member normally free from engagement with said strap 20 and having a free dull end, said member being movable in one direction for engagement of said dull end with the strap for forcing the latter through said openings and movable in the opposite direction away from said strap and without 25 retracting the latter through said openings.

HARRY ALFANDRE.
